UNITED STATES PATENT OFFICE.

FREDERICK E. AHLERING, OF PORT READING, NEW JERSEY.

FOUNTAIN SHAVING BRUSH.

Application filed February 28, 1922. Serial No. 539,951.

To all whom it may concern:

Be it known that I, FREDERICK E. AHLERING, a citizen of the United States, residing at Port Reading, in the county of Middlesex and State of New Jersey, have invented certain new and useful Improvements in Fountain Shaving Brushes, of which the following is a specification.

This invention relates to new and useful 10 improvements in fountain shaving brushes and has for its primary object to provide a simple and efficient valve means therein for controlling the passage of the liquid soap from the reservoir to the bristles of the 15 brush.

Another important object of the invention is to provide a bristle holder having means for uniformly distributing the liquid soap to all parts of the bristles.

20 Other objects and advantages of the invention will become apparent during the course of the following description.

In the accompanying drawing forming a part of the description and wherein like 25 numerals are employed to designate like parts throughout the several views;

Figure 1 is a perspective view of the improved brush.

Figure 2 is a longitudinal section through 30 the same.

Figure 3 is a transverse section through the device.

Figure 4 illustrates the valve assembly; and

35 Figure 5 is a perspective view of the bristle holder.

In the drawing wherein for the purpose of illustration is shown the embodiment of my invention which is at present preferred, the numeral 6 designates a tubular handle having opposite ends thereof internally screw threaded for the reception of a removable cap 7 at one end and a removable bristle holder 8 at the opposite end. If preferred, the cap 7 may be provided with a vent opening 9 to facilitate the discharge of liquid soap in a manner to be hereinafter set forth. The bristle holder consists of a cap shaped member 10 equipped with external screw threads for cooperation with the internal threads at one end of the handle. The bristles of the brush are vulcanized in rubber within the cap in the well known manner. The top of the cap is provided with a conical depression of substantial size to equip the bristle holder with a tapered

nipple which extends into the inner ends of the bristles which are fastened to the member 10. This nipple is equipped with a plurality of apertures to permit the liquid soap to pass from the handle into the bristles.

The handle of the brush is provided with a partition 13 which divides the handle into a liquid soap chamber 14 at the end 65 adjacent the cap 7, and a valve chamber 15 at the opposite end of the handle. This partition is provided with a central aperture as clearly seen in Figure 2, and forms a valve seat for a valve 16 movable longitudinally within the valve chamber.

This valve consists of a rod having a valve body 17 formed thereon and a point spaced from one end of the valve rod so that this end of the rod may enter the opening in the partition 13 and guide the valve. The rod is also provided with an abutment 18 arranged between the ends of the rod. The guide for the valve rod consists of an apertured extension 19 formed on the wall 75 of the valve chamber adjacent the outer end thereof. The lower end of the valve rod operates in this guide and the valve is normally retained upon its seat by means of a coiled spring 20 positioned upon the lower 80 end of the rod between the guide and the abutment 18.

In order that the valve can be readily actuated, a lever 21 is pivoted between its ends to extend through a slot in the valve 90 chamber end of the handle. One end of the lever is extended beyond the exterior of the handle and is there equipped with a button 22. The other end of the lever extends into the valve chamber and is provided with a 95 forked end 23 which is adapted to straddle the valve rod and normally rest upon the abutment 18.

Assuming that the reservoir 14 is filled 100 with liquid soap and it is desired to make a lather with the bristles, the latter are first moistened, after which the lever 21 is caused to pivot by pressure exerted thereon by the operator's finger to cause the inner end of the lever to bear down upon the abutment 105 and force the valve body 17 away from its seat so as to permit the liquid soap to pass through the aperture in the partition 13 and thence into the valve chamber. From here, the liquid soap is permitted to pass through 110 the tapered nipple 12 of the bristle holder and percolate out through the apertures

therein into the bristles. When a sufficient quantity of the liquid soap has been dispensed, pressure upon the valve operating lever 21 is released so that the spring 20 5 will promptly return the valve body to its seat and close the opening in the partition 13.

The foregoing description and the accompanying drawing have reference to the preferred or approved embodiments of my invention. It is to be understood however, that such changes may be made in construction and arrangement of parts, materials, dimensions, etc., as may prove expedient and 15 fall within the scope of the appended claim.

Having thus described and illustrated my invention, what I claim as new and desire to secure by Letters Patent is:

A fountain shaving brush comprising a 20 hollow handle having a partition therein equipped with a central aperture, said partition dividing the handle into a reservoir

and a valve chamber, a slot in the wall of the valve chamber, a bristle carrying part 25 associated with the outer end of the valve chamber, a guide in the valve chamber having an opening in alignment with the opening in the partition, a valve rod having a valve body adapted to seat against the partition, an abutment carried by the valve rod, a spring on the latter disposed between the 30 guide and the abutment to normally close the valve against the partition, and a lever pivoted to the handle and extending through the slot therein and having an end associated with the valve rod adjacent the abutment to operate thereon.

In testimony whereof I affix my signature in presence of two witnesses.

FREDERICK E. AHLERING.

Witnesses:

ELI LASHER,
ALFRED W. RODNEY.
